(57) **CLAIM**

The ornamental design for a power screw driver tool, as shown and described.

DESCRIPTION

FIG. 1 is a top, front, and left side perspective view of a power screw driver tool;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

Structure shown in broken lines in FIGS. 1-7 form no part of the claimed design.
